(57) **CLAIM**

The ornamental design for combination copier, scanner, printer, as shown and described.

DESCRIPTION

FIG. 1 is a perspective view of a combination copier, scanner, printer showing my new design;

FIG. 2 is another perspective view of the combination copier, scanner, printer;

FIG. 3 is a front view of the combination copier, scanner, printer;

FIG. 4 is a rear view of the combination copier, scanner, printer;

FIG. 5 is a right side view of the combination copier, scanner, printer;

FIG. 6 is a left side view of the combination copier, scanner, printer;

FIG. 7 is a plan view of the combination copier, scanner, printer; and,

FIG. 8 is a bottom view of the combination copier, scanner, printer.

The broken lines show portions of the design that form no part of the claim.

1 Claim, 8 Drawing Sheets
